UNITED STATES PATENT OFFICE.

SYLVANUS L. WOTRING, OF PROSPECT, AND CLARENCE H. SUTPHEN,
OF COLUMBUS, OHIO.

CHEMICAL-ENGINE.

No. 852,815.

Specification of Letters Patent.

Patented May 7, 1907.

Application filed May 23, 1906. Serial No. 318,302.

To all whom it may concern:

Be it known that we, SYLVANUS L. WOTRING and CLARENCE H. SUTPHEN, citizens of the United States, residing, respectively, at Prospect and Columbus, in the counties, respectively, of Marion and Franklin and State of Ohio, have invented certain new and useful Improvements in Chemical-Engines, of which the following is a specification.

Our invention relates to chemical engines and has for its object the provision of a hand chemical engine comprising a tank mounted upon wheels in such manner that said tank may be turned bodily over by a reversal of the framework upon which the tank is mounted.

Further objects and advantages of the invention will be set forth in the detailed description which now follows:

In the accompanying drawing: Figure 1 is a side elevation of a tank illustrating the parts in their normal position in full lines and illustrating the tank in its inverted position in dotted lines, Fig. 2 is a plan view of the engine, Fig. 3 is a longitudinal vertical section of the engine, and, Fig. 4 is an enlarged sectional view of an acid containing receptacle hereinafter described.

Like numerals designate corresponding parts in all of the figures of the drawing.

Referring to the drawing, the numerals 5 designate a pair of wheels which are connected by an axle 6. A framework is secured to this axle by bolts 7. This framework comprises a band 8 which is made in two sections, said band encircling a tank 9. Forwardly extending bars 10 are secured to the band and to the axle as at 11. The front ends of the bars 10 are secured in couplings 12, these couplings being connected by a transverse bar 13. Mounted to turn upon this bar 13 are couplings 14 into which are threaded bars 15, said bars 15 being connected by a transversely disposed bar 16, the ends of which are threaded into couplings 17. As is best illustrated in Fig. 2, the ends of the transversely disposed bar 13 project beyond the couplings 12 upon each side to form handles 18.

Carried upon the rear side of the tank is a bracket 19 which normally serves to support a coil of hose 20, one end of the hose being connected to the tank as at 21. The top of the tank has an internally threaded opening 22

formed therethrough which is adapted to receive a plug 23. As is best illustrated in Fig. 4, this plug on its outer face carries ears 24 adapted to receive a handle 25. A gasket 26 is arranged upon the inner face of this plug. Secured to the inner face of the plug by a screw 27 are spring clips 28 which are adapted to snap beneath the under side of an acid containing receptacle 29. A lead stopper 30 is slidably disposed between these spring clips and is adapted to close the neck of the bottle by its own weight when the parts are in the position illustrated in Fig. 3. When the tank is inverted, this stopper falls to the position illustrated in Fig. 4 and permits the acid to flow from the receptacle 29 into the body of the tank in the usual and well known manner.

A box 31 for carrying extra acid bottles is secured upon hangers 32, said hangers being pivoted upon trunnions 33 which are carried by the bars. By virtue of this construction the box will remain in an upright position even when the bars are swung to their dotted line position in Fig. 1.

The operation of the device is as follows: The device having been charged by placing 80 within the tank 9 the proper chemicals and the acid containing receptacle 29 having been placed in the position shown in Fig. 3, by screwing the plug 23 into the threaded opening 22 of the tank, the device is ready for use 85 and when at rest the parts are in the position illustrated in full lines in Fig. 1, at which time the auxiliary handle formed by the bars 15 and 16 serves as a support to hold the bars 10 in a substantially horizontal position, as 90 will be readily understood. When an alarm of fire is given, this support forms an auxiliary handle which, together with the handles 18, enable the firemen to secure a sufficient hold upon the engine. When the fire is 95 reached, the framework of the engine is thrown bodily over, so that the bars 10 lie in the position illustrated in dotted lines in Fig. 1. This of course inverts the tank and permits the well known mixing of the chemicals 100 therein. At this time, the auxiliary handle again serves as a support to hold the tank in its inverted position while the engine is in use.

From the foregoing description, it will be 105 seen that the simple mounting herein pro-

vided, permits a large tank to be used, while rendering said tank easy of transportation and easy to invert.

While the elements shown and described are well adapted to serve the purposes for which they are intended, it is to be understood that the invention is not limited to the precise construction set forth, but includes within its purview such changes as may be made within the scope of the appended claims.

What I claim, is:

1. The combination with a wheeled frame, of a fire extinguisher mounted upon said frame and set in operation by the inversion thereof, said fire extinguisher being adapted to be inverted by swinging said frame from one side of the wheels to the other side thereof and means for supporting said frame in a horizontal position at each of its limits of movement.

2. The combination with a wheeled frame, of a fire extinguisher which is set in operation by the inversion thereof and which is mounted upon said frame, both the top and the bottom of said fire extinguisher lying within the circumference of said wheels and a handle portion pivoted to the outer end of the wheeled frame and adapted to support said frame in a horizontal position at each of its limits of movement.

3. The combination with a wheeled frame,

of a fire extinguisher mounted upon said frame and set in operation by the inversion thereof, said fire extinguisher being adapted to be inverted by swinging said frame from one side of the wheels to the other side thereof, and a downwardly extending handle which is pivotally connected to the outer end of said wheeled frame, said handle being adapted to support said frame in a horizontal position at each of its limits of movement.

4. The combination with a wheeled frame, of a fire extinguisher mounted upon said frame and set in operation by the inversion thereof, said fire extinguisher being adapted to be inverted by swinging said frame from one side of the wheels to the other side thereof, the tank of said fire extinguisher being of such dimensions as to lie entirely within the circumference of the wheels, and a downwardly extending handle which is pivotally connected to the outer end of said wheeled frame, said handle being adapted to support said frame in a horizontal position at each of its limits of movement.

In testimony whereof we affix our signatures in presence of two witnesses.

SYLVANUS L. WOTRING.
CLARENCE H. SUTPHEN.
